[57] CLAIM

The ornamental design of a pump impeller housing, substantially as shown and described.

DESCRIPTION

FIG. 1 is a left side view of a pump impeller housing showing my new design, the right side and top and bottom plan views being identical thereto;

FIG. 2 is a left end view thereof;

FIG. 3 is a right end view thereof, and

FIG. 4 is a section view thereof taken along line 4—4 of FIG. 2.

FIG. 1FIG. 4FIG. 2FIG. 3
